Primary Examiner—T. Chase Nelson*Assistant Examiner*—David G Muller(74) *Attorney, Agent, or Firm*—Griffiths & Seaton PLLC(57) **CLAIM**

The ornamental design for a transaction card, as shown and described.

DESCRIPTION

FIG. 1 is a front, perspective view of a transaction card showing an embodiment of our new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The features shown in broken lines depict environmental subject matter only and form no part of the claimed design.
